UNITED STATES PATENT OFFICE

WILHELM B. BRONANDER, OF MONTCLAIR, NEW JERSEY

FIRE EXTINGUISHER SUPPORT

Application filed April 15, 1929. Serial No. 355,166.

This invention relates to fire extinguisher supports.

More particularly stated, the invention relates to the grenade type of fire extinguisher and to a holder or support for the grenade.

This invention has for its salient object to provide a support for a grenade, so constructed and arranged that in case of fire the grenade will automatically drop, break and dispense the fire extinguishing fluid.

Another object of the invention is to provide a bracket or holder for grenades comprising few parts and a structure that can be economically manufactured.

Another object of the invention is to provide a support or holder for grenades so constructed and arranged that it can be suspended from a ceiling.

Further objects of the invention will appear from the following specification taken in connection with the drawings, which form a part of this application, and in which

Fig. 1 is an elevational view of a device constructed in accordance with the invention;

Fig. 2 is a view similar to Fig. 1 but taken at right angles thereto;

Fig. 3 is a top plan view of the device shown in Fig. 1;

Fig. 4 is a detail elevation on an enlarged scale showing one manner of securing the supporting rods against separation by a fusible element; and

Fig. 5 is a sectional elevation taken substantially on line 5-5 of Fig. 4.

The invention briefly described consists of a support for a grenade fire extinguisher comprising a member adapted for suspension from a ceiling or other fixed supporting structure, and a pair of rods, preferably formed of wire stock, carried by the support and secured against separation by means including a fusible connection. In case of fire, the fusible connection will give way, permitting the rods to separate, thus releasing the grenade. The grenade is formed of frangible material, such as glass, and upon release it will fall and break, thus freeing the fire extinguishing liquid.

Further details of the invention will appear from the following description.

In the embodiment of the invention illustrated, the device is suspended from a ceiling or other supporting structure by a bail 10 provided with a loop 11 for engaging a supporting hook. The bail 10 has secured to its lower ends, a pair of rods 14 and 15, curved as shown in Fig. 3, to embrace a frangible grenade 16. The lower ends 17 and 18 of the bail are preferably bent around the rods, as shown in Fig. 1.

The ends of the rods 14 and 15 are preferably disposed in substantially parallel relation and each pair of ends is engaged by a plate 20 having a hole or opening 21 adapted to receive one of the pair of ends and having secured to its opposite side edge 24 by means of a fusible connection 23, a strip 25 provided with an opening 26 for receiving the other 70 of the pair of ends.

The edge 24 of the plate 20 has a slot or notch 28 and the strip 23 has a tongue 30 extending through the notch and engaging over the inner edge thereof, as clearly illustrated 75 in Fig. 5.

The wire rods 14 and 15 are preferably formed of resilient material and are held under tension by the two securing plates 20. In case of fire, the fusible connection 23 on one or both of the plates 20 will melt, thus releasing the strip or strips 25, permitting the ends of the rods to spring outwardly and thus release the grenade 16.

It will be evident that in case of fire in a room where one of the extinguishers is suspended in the manner set forth, the heat from the fire will rise rapidly to the ceiling, thus causing the grenade to be released.

Although one specific embodiment of the invention has been particularly shown and described, it will be understood that the invention is capable of modification and that changes in the construction and in the arrangement of the various cooperating parts 95 may be made without departing from the spirit or scope of the invention, as expressed in the following claims.

What I claim is:

1. A support for frangible fire extinguish-

- er grenades comprising a member adapted for suspension from a ceiling, a pair of rods carried by said member and shaped to embrace the grenade, and means for securing said rods against separation in grenade supporting position, said means including a fusible element at each end of said rods.
5. A support for frangible fire extinguisher grenades comprising a bail adapted for suspension from a ceiling and having separated ends, a rod carried by each end of the bail, said rods being shaped to embrace a grenade, and means independent of said bail for securing said rods against separation in grenade supporting position, said means including a fusible element.
10. A support for frangible fire extinguisher grenades comprising a bail adapted for suspension from a ceiling and having separated ends, a rod carried by each end of the bail, said rods being shaped to embrace a grenade, and means independent of said bail for securing said rods against separation in grenade supporting position, said means including a fusible element.
15. A support for frangible fire extinguisher grenades comprising a bail formed of resilient material and adapted for suspension from a ceiling and having separated ends, a rod carried by each end of the bail and formed of resilient material, said rods being shaped to embrace a grenade, and means independent of said bail for securing said rods against separation in grenade supporting position, said means including a fusible element.
20. A support for frangible fire extinguisher grenades comprising a bail formed of resilient material and adapted for suspension from a ceiling and having separated ends, a rod carried by each end of the bail and formed of resilient material, said rods being shaped to embrace a grenade, and means independent of said bail for securing said rods against separation in grenade supporting position, said means including a fusible element.
25. A support for frangible fire extinguisher grenades comprising a bail formed of resilient material and adapted for suspension from a ceiling and having separated ends, a rod carried by each end of the bail and formed of resilient material, said rods being shaped to embrace a grenade, and means independent of said bail for securing said rods against separation in grenade supporting position, said means including a fusible element.
30. A support for frangible fire extinguisher grenades comprising a bail having a loop intermediate the ends thereof adapted for suspension from a ceiling and having separated ends, a rod carried by each end of the bail, said rods being shaped to embrace a grenade, and means independent of said bail for securing said rods against separation in grenade supporting position, said means including a fusible element.
35. A support for frangible fire extinguisher grenades comprising a bail having a loop intermediate the ends thereof adapted for suspension from a ceiling and having separated ends, a rod carried by each end of the bail, said rods being shaped to embrace a grenade, and means independent of said bail for securing said rods against separation in grenade supporting position, said means including a fusible element.
40. A support for frangible fire extinguisher grenades comprising a bail having a loop intermediate the ends thereof adapted for suspension from a ceiling and having separated ends, a rod carried by each end of the bail, said rods being shaped to embrace a grenade, and means independent of said bail for securing said rods against separation in grenade supporting position, said means including a fusible element.
45. A support for frangible fire extinguisher grenades comprising a member adapted for suspension from a ceiling, a pair of rods carried by said member and supported intermediate the ends of the rods, said rods being shaped to embrace the grenade, and means at each end of said rods for retaining said rods against separation, the means at one end including a fusible element.
50. A support for frangible fire extinguisher grenades comprising a member adapted for suspension from a ceiling, a pair of rods carried by said member and shaped to embrace the grenade, and means at each end of said rods for retaining said rods against separation and in grenade supporting position, each of said means including a fusible element.
55. A support for frangible fire extinguisher grenades comprising a member adapted for suspension from a ceiling, a pair of rods carried by said member and shaped to embrace the grenade, and means at each end of said rods for retaining said rods against separation and in grenade supporting position, each of said means including a fusible element.
60. A support for frangible fire extinguisher grenades comprising a member adapted for suspension from a ceiling, a pair of rods carried by said member and shaped to embrace the grenade, and means at each end of said rods for retaining said rods against separation and in grenade supporting position, each of said means including a fusible element.
65. WILHELM B. BRONANDER.
